UNITED STATES PATENT OFFICE.

JULIAN F. DENISON, OF NEW HAVEN, CONNECTICUT, ASSIGNOR OF ONE-HALF TO JOHN E. MAR, OF WEST HAVEN, CONNECTICUT.

STARTING DEVICE FOR EXPLOSIVE-ENGINES.

No. 893,712.

Specification of Letters Patent.

Patented July 21, 1908.

Application filed December 13, 1904. Serial No. 236,054.

To all whom it may concern:

Be it known that I, JULIAN F. DENISON, a citizen of the United States, residing at New Haven, in the county of New Haven and State of Connecticut, have invented certain new and useful Improvements in Starting Devices for Explosive-Engines, of which the following is a specification, reference being had therein to the accompanying drawings.

10 My invention relates to new and useful improvements in explosive engines, and refers more especially to means whereby air may be used for starting an engine of this character; its object being, among other things, 15 to provide an explosive engine with such devices as will permit the engine to be started instantly by the opening of a valve without resorting to the usual procedure of manually rotating the shaft while the explosive mixture 20 is being formed; a further object being to accomplish these results by mechanism that can be economically constructed and readily assembled.

To these, and other ends, my invention 25 consists in the explosive engine having certain details of construction and combination of parts as will be hereinafter described and more particularly pointed out in the claims.

Referring to the drawings, in which like 30 numerals of reference designate like parts in the several figures; Figure 1 is a front elevation of an explosive engine having my improvements attached thereto; Fig. 2 is a transverse sectional elevation of one of the 35 cylinders, taken upon line A—B of Fig. 1; Fig. 3 is an enlarged sectional view of the valve mechanism, taken upon line C—D of Fig. 4; and Fig. 4 is a sectional elevation of the same mechanism, taken upon line E—F of Fig. 3.

In certain types of explosive engines it is the practice to start them by manually imparting a number of rotations to the crank shaft, and to continue this manual operation 45 until the vaporizer has produced a mixture, the explosion of which will operate the piston. In engines of small size the labor required is not very great, but in large engines the labor required is so considerable that it 50 is a serious detriment to the adoption of this type of engine where they would otherwise be applicable.

Explosive engines have been heretofore devised with devices attached thereto where- 55 by one or more of the pistons in the series are

operated by means of air pressure while the balance of the pistons are being operated as gas engines, and as the pistons are successively operated by gas, the air valves are shut off manually and the pistons previously 60 operated by air are then operated as usual by the explosive compound.

In my invention I provide means, preferably a valve, whereby the air will be admitted into each of the cylinders in succession, 65 which air is under sufficient pressure to operate the piston and through it the engine until such time as the vaporizers have produced a mixture, the explosion of which will be of sufficient pressure to operate the piston, 70 at which time the air pressure will be automatically shut off and the piston will continue its operations in the usual manner by the explosion of the mixture. By this device the engine will be started and propelled by the air, 75 which does not interfere with the production of the explosive mixture, which, as soon as completed, is exploded by a spark, and the pressure being greater than the air pressure, automatically closes the air valve and shuts 80 off the air pressure. Under this construction one or more of the pistons in the series may be operating by air pressure while the balance of the pistons are operating by the explosive mixture. This was impracticable 85 under the old methods of starting and operating explosive engines.

My invention is especially applicable to a two-cycle type of engine wherein the air is sucked in below the piston, and during the 90 down movement thereof is compressed until a port is uncovered, at which time it passes through the ports from below the piston to above the same and is afterwards exploded. An engine of this general type is illustrated 95 in the drawings, wherein the numeral 1 designates the cylinder, 2 the piston, 3 the crank shaft, 4 the connection between the crank shaft and the piston, 5 the pipe leading from the vaporizer, 6 the exhaust pipe, 7 the cylinder head, and 8 the sparkler. All of these parts operate in a well-known manner, *i. e.*, the explosive mixture passes through the pipe 5 and enters the chamber 6, from which it passes into the bottom 9 of the engine 100 whereon the crank rotates. During the downward movement of the piston, the charge is compressed and when the end of the down stroke of the piston is reached the port 10 is uncovered and the explosive mixture 105

escapes from beneath the piston to the top of the cylinder. The return movement of the piston again compresses the charge and at the proper time the sparking mechanism explodes the same, which causes the piston to move downwardly again, and just before the piston uncovers the port 10 it uncovers the port hole 11 which permits the products of the exploded charge to pass out through 10 the exhaust pipe 6.

The improvements devised by me for accomplishing the ends hereinbefore noted comprise a valve body 12 which is secured to the cylinder head 7, and having a boss 13 thereon which projects into an opening 14 in the side of the cylinder head. Operative within said body is the horizontal valve 15, the stem 16 of which is supported in the bearing 17 fixed to the body 12. Secured to said 15 stem is the collar 18 between which and a part of said body 12 is a coil spring 19 which normally holds said valve 15 against its seat. Also mounted within said body is a vertical valve 20 having a stem 21 attached thereto 20 which passes through the packing gland 22 fixed to said body member, and surrounding said stem is suitable packing for preventing the leakage of air therethrough. Connecting the valves 20 and 15 is the chamber 23 for the 25 passage of air from one valve to the other. Motion is imparted to the valve 20 through the rod 24 which engages one end of the valve stem 21 during a portion of its stroke and is threaded at the other end in a strap 25 30 that encircles the eccentric 26 fixed to the shaft 27 that is rotatably mounted in integral lugs 28. The shaft 27 is rotated from the crank shaft 3 which is provided with the usual driving pulley 43. Any of the many 35 forms of reversing mechanism may be used to connect the shafts 3 and 27, and I do not claim the details thereof as any portion of my invention, but as shown herein, the mechanism comprises a sprocket chain 29 which is 40 connected with the sprocket wheel 30 upon the shaft 3, and a sprocket wheel 31 fixed to the shaft 27, and runs against an idler wheel 32 fixed to a lever 33 rotatably mounted upon the shaft 27, and having a handle 34 whereby 45 the said lever may be manipulated.

The particular form of mechanism for reversing herein shown is to be made the subject of another application.

Affixed to one of the cylinders is an air 50 pump comprising a cylinder 35 having a piston operative therein and rod 36 which is connected with a strap 37 encircling an eccentric 38 fixed to said shaft 3. This air pump may be operated independently of the 55 gas engine if desired, or connected therewith as herein shown, and any form or type of air pump may be used within my invention. Connecting all of the valve bodies 12 is the 60 pipe connection 39 which is joined to the air 65 pump by the piping 40 and air cock 41. The

air pump is also connected by the pipe 42 with a suitable air tank or reservoir (not shown), whereby compressed air may be stored. In operation a supply of air under the required pressure is maintained within the air tank so that to start the engine the air cock 41 is opened and the air in the tank passes therefrom through the pipe 42 and air cock 41 into the pipe connection 39 and thence into the air chamber 23 in the valve 75 body 12. There being a series of cylinders and the valves 20 being operated from the eccentrics 26 which are arranged about the shaft 27 at varying angles to each other, some of the valves 20 will be off their seat so 80 that the air pressure can pass therethrough. This air pressure after it passes through the chamber 23 forces the valve 15 off its seat and permits the air to enter the cylinder above the piston, and this pressure is sufficient to operate said piston and impart a 85 rotation to the crank shaft. After the engine has started, the valves 20 connected with the other cylinders are opened successively by the rotation of the shaft 27, thus 90 permitting the air to enter each of said cylinders and successively operate the pistons therein. This continues until the explosive mixture has been formed by the vaporizing mechanism and has entered any 95 one of the cylinders and the sparking mechanism has exploded the same, at which time the pressure generated by the explosion of the mixture is greater than the air pressure, hence the valve 15 is forced and 100 held onto its seat and the air supply automatically shut off and the engine continues to operate as an explosive engine as a result of the successive explosions. If perchance the vaporizer connected with any one of the 105 cylinders should fail to operate the stored air pressure would immediately force the valve 15 off its seat and that particular cylinder would continue to operate by means of the air pressure. The supply of 110 air that is conveyed to the pipe connection 39 may be derived from any source and can be taken from the cylinders themselves by diverting part of the explosion to a tank or reservoir through a pipe without materially 115 reducing the power of the engine, and frequently where engines of this character are used a quantity of compressed air is used for other purposes and connection can be made in any of the ways convenient and 120 most desirable, but where an air supply is not maintained I have provided the pump mechanism previously mentioned whereby a supply of compressed air may always be had in the tank or reservoir located adjacent 125 to the engine.

There are many minor changes and alterations that can be made within my invention aside from those herein suggested, and I would therefore have it understood that I 130

do not limit myself to the exact construction herein shown and described, but claim all that falls fairly within the spirit and scope of my invention.

Having described my invention, what I claim as new, and desire to secure by Letters Patent, is:

In an explosive engine, the combination of a plurality of cylinders, a source of fluid pressure supply; means for admitting fluid pressure into each of said cylinders in succession to start said engine, said means comprising a valve-plug inserted in the side wall of each cylinder respectively, a common valve-controlled connection between the fluid pressure supply and each of said valve plugs, a passage in each plug opening into the cylinder, a valve controlling said passage normally spring-pressed to seated position, and adapted to be actuated in either direction by fluid pressure, a second passage connecting said valve plug with the pressure

connection aforesaid, a valve controlling said passage and having a stem projecting outside of the plug, a spring between the outer end of said stem and the plug tending to seat the valve; a passage connecting the aforesaid two passages in the plug; a cap-plate for said plug providing a guide for the first mentioned valve in the plug; an eccentric and rod for each of said last named valve-stems operated from the crank shaft of the engine, said eccentrics being so relatively disposed upon the shaft that one of said valve stems will be actuated by its corresponding rod in every rotatable position of the shaft, and means for guiding said rods.

In testimony whereof I affix my signature in presence of two witnesses.

JULIAN F. DENISON.
